C. W. GROBE,
LETTERING BRUSH.
APPLICATION FILED JULY 13, 1917.

1,260,189.

Patented Mar. 19, 1918.

Inventor
Charles W. Grobe.

Attorney

UNITED STATES PATENT OFFICE.

CHARLES W. GROBE, OF TROY, NEW YORK.

LETTERING-BRUSH.

1,260,189.

Specification of Letters Patent. Patented Mar. 19, 1918.

Application filed July 13, 1917. Serial No. 180,318.

To all whom it may concern:

Be it known that I, CHARLES W. GROBE, a citizen of the United States, residing at Troy, county of Rensselaer, and State of New York, have invented certain new and useful Improvements in Lettering-Brushes, of which the following is a specification.

Reference may be had to the accompanying drawings, and the reference characters marked thereon, which form a part of this specification. Similar characters refer to similar parts in the several figures therein.

The invention relates to a lettering-brush having a body of flexible fibrous brush-material which flattens or spreads in use so as to make a line or stroke of considerable width.

The principal object of the invention is to cause the ink-distributing end-edge portion of the brush to automatically maintain a position substantially at right angles to the direction of its progressive movement in forming curves.

Other objects will appear in connection with the following description.

Figure 1 of the drawings is a view in front elevation of a lettering-brush embodying my invention.

Fig. 2 is a central longitudinal section of the same taken on the broken line 2-2 in Fig. 1.

Fig. 3 is a cross-section of the same taken on the broken line 3-3 in Fig. 1.

Fig. 4 is a view in elevation of a lettering-brush embodying my invention having a circular or cylindrical body of fibrous brush-material.

Fig. 5 is a similar view illustrating the manner in which said body of fibrous brush-material spreads or flattens in use so as to produce a line or stroke of considerable width.

Referring to Figs. 1 to 3 of the drawings wherein the invention is shown in preferred form, 1 is the brush-head, carrying a body of hair or bristles, 2, for distributing the ink.

In this form of my invention, both the brush-head and the body, 2, of brush-material are made flat.

The head is made hollow as shown, with an inlet aperture, at 3, whereby a supply of ink can be inserted within the head, which ink flows out through the hair as the brush is moved over the surface to be lettered.

The brush-head, 1, is fixed upon a spindle,

4, which spindle is rotatively mounted within a bushing, 5, inserted within an aperture in the handle, 6.

A coil-spring, 7, is interposed between the inner end of the bushing, 5, and a head, 8, on the inner end of the spindle, 4, said spring tending to draw the brush-head against the outer end of the bushing, 5, with sufficient force to prevent the brush-head from rotating upon the handle by gravity alone, yet leaving the brush-head free to respond to the rotative influence due to its frictional engagement with a surface over which the brush is being moved.

As thus constructed, when the brush is moved in a curved line along the surface to be lettered, it is necessary only for the user to draw the handle of the brush along the desired curved path while holding the handle substantially perpendicular to the surface on which the brush rests, and the frictional engagement of the brush with the surface over which the brush is traveling will cause the brush-head and flat brush to automatically adjust themselves to maintain the ink-distributing end-edge of the brush at right angles to the direction of movement, causing the ink-distributing portion of the brush to make a line of substantially uniform width in traversing such curved lines.

It is thus unnecessary for the user to rotate the handle of the brush in order to cause the brush-head to gradually change direction in traversing a curved path, which is a difficult operation and requires much skill.

By having the brush swiveled and self-adjustable upon the handle in this respect, persons with little or no experience are able to produce satisfactory lettering.

I have shown a slide-pin, 9, mounted to slide longitudinally in a slideway, 10, on the handle, which slide-pin is engageable with an aperture, 11, to lock the brush-head against rotative movement when desired.

When it is desired to operate the brush in the manner above described in making curved lines, this slide-pin, 9, is withdrawn from the aperture, 11, leaving the brush-head free to rotate upon the handle.

For the purpose of producing shaded letters of a plurality of colors, I provide the brush-head with a plurality of ink-feeding devices, as by extending through the head a supply-tube, 12, leading to a part only of the bristle or hair, which supply-tube can carry a supply of ink of a different color from

that within the main ink-reservoir formed within the hollow brush-head.

The operation of the device is as follows: For plain lettering by straight lines, the 5 slide-pin, 9, is slid into the aperture, 11, and the brush used as any ordinary paint brush or lettering-brush is used.

When it is desired to make curved lines, the slide-pin, 9, is withdrawn from the aperture, 11, and the brush is drawn by the hand 10 of the operator along the surface to be lettered, the operator drawing the handle of the brush along the desired curved path with the body of hair or bristles in contact with 15 the surface to be lettered.

In this operation the handle is held substantially perpendicular to the surface on which the brush rests, with the body of hair trailing flatly upon said surface. This 20 causes the brush-head to automatically rotate upon the handle so as to maintain its ink-distributing end-edge approximately at right angles to its progressive movement, and hence to make a line of substantially 25 full width throughout its progressive movement.

The body of hair or bristles preferably projects from the brush-head in a plane oblique to the plane of the handle; and I 30 also prefer to have the brush-head itself mounted upon its spindle, 4, in a plane somewhat oblique to said spindle and the handle.

For the purpose of controlling the flow of ink through the supply-tube, 12, a valve-screw, 13, may be employed, inserted within 35 a screw-threaded aperture intersecting the tube.

In Figs. 4 and 5, I have shown my invention applied to a brush having a substantially cylindrical body of flexible fibrous brush-material such as hair or bristles, which body is adapted to spread and flatten in use 40 as shown in Fig. 5, whereby it is adapted to form a stroke or line of considerable 45 width, which line, as the brush traverses a curved path, will vary greatly in width unless the flattened body of brush material is kept at substantially right angles to the line of progressive movement of the brush.

50 The brush when thus flattened in use is open to the same objections as the flat brush heretofore described; and I am able to overcome these objections substantially in the same manner above described.

55 I thus mount the cylindrical brush-head,

14, upon a spindle, 15, which spindle is rotatively mounted within the handle, 16, in substantially the same manner as above described with respect to the spindle, 4, in the handle, 6.

60 By holding the handle substantially perpendicular to the surface over which the brush travels, and by flattening the brush-body upon said surface, the brush-body will be caused to trail after the handle, and this 65 will cause the brush-head to automatically rotate upon the handle so that the flattened ink-distributing end-edge of the trailing brush-body will maintain a position approximately at right angles to its progressive 70 movement, and hence will make a line or stroke of substantially full width throughout its progressive movement whether that movement be in a straight line or a curved line.

75 The same handle may be adapted for use with different brush-heads interchangeably, by providing a screw-connection between the brush-head and the spindle whereby the brush-head is rotatively mounted upon the handle, such a screw-connection being shown at 17, in Fig. 4.

What I claim as new and desire to secure by Letters Patent is—

1. A device of the class described having 85 a handle; a brush-head freely swiveled upon the handle; and a body of flexible fibrous paint-brush-material mounted on the brush-head.

2. A device of the class described having 90 a handle; a brush-head freely mounted upon the handle upon an axis extending longitudinally of the handle; and a flat body of paint-brush-material mounted on the brush-head.

3. A device of the class described having 95 a handle; a brush-head freely swiveled upon the handle; and a flat body of paint-brush-material projecting from the brush-head obliquely to the handle.

4. A device of the class described having 100 a handle; a brush-head freely swiveled upon the handle projecting obliquely therefrom; and a flat body of paint-brush-material projecting from the brush-head obliquely to the 105 handle.

In testimony whereof, I have hereunto set my hand this 10th day of July, 1917.

CHAS. W. GROBE.
